BALLOON INFLATOR

Edward E. Elson, Anaheim, Bert Lane, Palm Springs, and George H. Karlin, Beverly Hills, Calif., assignors to Automatic Helium Balloon Systems, Inc., Beverly Hills, Calif.

Filed Oct. 23, 1970, Ser. No. 25,616

Term of patent 14 years

Int. Cl. D15—02

U.S. Cl. D65—1

FIG. 1 is a front elevational view of a balloon inflator showing our new design;

FIG. 2 is an elevational view taken from one side thereof, the opposite side being the same as the side shown; and FIG. 3 is a rear elevational view.

We claim:

The ornamental design for a balloon inflator, as shown and described.
